DESIGN FOR A SEA FOOD PICK

Malcolm W. Lowenstein, Baltimore, Md., assignor
of one-half to Samuel Silberstein, Baltimore,
Md.

Application December 29, 1936, Serial No. 66,783

Term of patent 7 years

To all whom it may concern:

Be it known that I, Malcolm W. Lowenstein, a citizen of the United States, residing in Baltimore, in the State of Maryland, have invented a new, original, and ornamental Design for a Sea Food Pick, of which the following is a specification, reference being had to the accompanying drawing, forming part thereof:

Fig. 1 is a view in front elevation of a sea food pick embodying my new design.

Fig. 2 is a side view of the same.

Fig. 3 is a view in rear elevation thereof.

I claim:

The ornamental design for a sea food pick, as shown.

MALCOLM W. LOWENSTEIN.
